UNITED STATES PATENT OFFICE.

HARRY A. BURGESS, OF GOODLAND, INDIANA, ASSIGNOR TO ROMINE MANUFACTURING CO., OF GOODLAND, INDIANA, A CORPORATION OF INDIANA.

PORTABLE GATE.

1,419,013.

Specification of Letters Patent. Patented June 6, 1922.

Application filed April 29, 1920. Serial No. 377,461.

To all whom it may concern:

Be it known that I, HARRY A. BURGESS, a citizen of the United States, residing at Goodland, in the county of Newton and 5 State of Indiana, have invented new and useful Improvements in Portable Gates, of which the following is a specification.

This invention relates to portable knock-down gates particularly applicable for farm 10 use and the prime feature of the invention is the provision of metallic parts so constructed that they may be carried in stock and sold independently of the bars employed for forming the body of the gate, said metallic 15 parts being so constructed that they may be quickly assembled with the bars to form the gate.

A further feature of the invention is in so constructing the various parts of the gate 20 structure that no bolts or pins will be entered through the bars of the gate for holding the parts in assembled position, said bars having freedom of movement in one direction so that when lifting action is exerted at the 25 free end of the gate, said end may be elevated for forming a passage below the gate, the parts of the gate assuming a rigid state when again lowered to natural position.

A further feature of the invention is the 30 provision of means for vertically adjusting the bars of the gate for supporting and maintaining the same in a normally horizontal position, tensioning means being provided, in conjunction with the adjusting means, for 35 holding the parts of the gate in assembled formation.

A further feature of the invention is in so constructing the metal parts of the gate that they may be used in connection with bars of 40 varying lengths for producing a gate of greater or less length.

A further feature of the invention is the provision of a latch structure that will automatically operate to lock the gate in closed 45 position when the gate is swung to closed position from either direction, the locking member being positive in its operation and operable manually for releasing the gate.

Other objects and advantages will be hereinafter more fully set forth in the accompanying specification.

In the accompanying drawings which are made a part of this application,

Figure 1 is a perspective view of a gate 55 applied to use.

Fig. 2 is a top plan view of the gate.

Fig. 3 is an enlarged sectional view as seen on line 3—3, Fig. 2.

Fig. 4 is an enlarged sectional view as seen on line 4—4, Fig. 2.

Fig. 5 is a side elevation of the gate with the free end thereof elevated to provide a 60 passage below the gate.

Fig. 6 is an enlarged sectional view as seen on line 6—6, Fig. 5.

Fig. 7 is a front elevation of a gate latch, showing one position of the locking part in full lines and another position in dotted lines.

Fig. 8 is a top plan view of the latch.

Fig. 9 is a front elevation of the gate latch with the locking member removed.

Fig. 10 is a top plan view of the parts shown in Fig. 9.

Referring to the drawings in which similar reference numerals designate corresponding parts throughout the several views, 1 and 2 indicate respectively the front and rear end frame members of the gate, which are preferably substantially U-shaped in 75 cross section, 3 indicates a pair of brace members, preferably positioned at the longitudinal center of the gate structure and 4 indicates a pair of supporting members, positioned adjacent the rear end of the gate 80 structure, the members 3 and 4 being preferably angular shaped in cross section, said parts being formed of metal.

Passing between the pairs of members 3 and 4, are bars 5, preferably of wood or 90 similar light material, the ends of said bars entering the frame members 1 and 2 and having free movement therein and these bars may be made of any preferred length, width and thickness as may be desired so 95 that gates of different lengths may be produced by merely changing the bars from one length for bars of another length, the same frame members or metal parts being used in all instances.

The bars 5 are held in proper spaced relation by means of pins 6 and 7, which are passed transversely through the end member 1 and the brace members 3, respectively, there being a pin above and one below each 105 bar 5, but not passing through the bars so that the ends of the bars 5 entering the frame member 2 may be raised or lowered as desired without interfering with the movement of the parts and the bars removed 110

or inserted without removing any of the pins.

The frame member 2 and the supporting member 4 are provided with transversely extending bolts or pins 8 and 9, respectively, which pass entirely through said members, the bolts 8 in the member 2 passing above the inner ends of the bars 5, while the bolts 9 in the member 4 pass below the bars, these bolts forming fulcrums for the bars 5 so that when lifting action is given the supports 4, the outer ends of the bars 5 will be elevated to maintain the gate structure in a substantially horizontal position at all times.

This manner of arranging the bolts 8 and 9 also leaves the bars 5 free to pivot on the bolts 9 when the outer end of the gate structure is elevated as shown in Fig. 5 without disturbing or changing the positions of the parts 2 and 4.

The supporting members 4 are adjusted vertically through the medium of a clevis 10, the arms of which pass on opposite sides of the pair of supporting members and engaged with one of the bolts 9 while the upper end thereof is engaged with the hook terminal 11 of an adjusting bolt 12, the outer end of the bolt 12 extending through the wall of the frame member 2 and having a nut 13 threaded thereon, which, when rotated, will adjust the bolt lengthwise and raise or lower the supporting members 4 and parts associated therewith.

The supporting members are held in spaced relation with the frame member 2 by means of straps 14, which are arranged in pairs and the ends thereof are bolted or otherwise secured to the member 2 and supports 4 respectively, said straps having pivoting action so that the supports will have free vertical movement.

The end section 1 is held in position over the outer ends of the bars 5 and the brace members 3 are held in stationary position by means of stay wires 14^a and 15 at the top and bottom, respectively, of the gate structure, the rear ends of said wires being attached to stirrups 16 at the upper and lower ends of the supporting members 4 and at their outer ends to tensioning hooks 17, which extend through the wall of the frame member 1 and have nuts 18 threaded thereon for giving longitudinal adjustment. The wires 14^a and 15 are preferably made in two sections and the meeting ends of the two sections looped around pins 19 and 20 at the upper and lower ends of the brace members 3, although it will be understood that each wire may be made in one piece and looped around or otherwise fastened to the pins 19 and 20. By this construction the brace member 3 is not only held in position, but the end member 1 is forced against the ends of the bars 5 and the opposite ends

thereof forced into the member 2, thus giving a more or less rigid gate structure and the wires 14^a and 15 may be tightened or loosened from time to time as desired.

The gate structure is suspended from a post 21 by hinges, each comprising a socket member 22 and bolt member 23, the socket members being attached in any suitable manner to the frame section 2, while the bolt members are attached to the post, and as the major portion of the weight is suspended from the upper bolt, said bolt is extended entirely through the post and threaded to receive locking nuts 24, one at each side of the post for locking the upper bolt against longitudinal movement. As all the strain on the lower hinge bolt is inwardly, it is not necessary to extend it entirely through the post, consequently the end of this bolt is preferably sharpened and driven a distance into the post.

This gate is adapted to swing either to the right or left when moving to open or closed position, hence it is necessary to provide a latch structure that will automatically stop the swinging movement of the gate and lock the gate against further swinging movement in either direction until the latch proper is operated manually for releasing the gate, the end of the latch proper engaged by the gate, as it swings to closed position, being free to move upwardly while the opposite end is held against upward movement, thus forming a positive stop for the gate.

In carrying out this construction a plate 25 is attached to a post 26 in any preferred manner, the lower edge portion of the plate having an upwardly bowed track 27 upon which a shank 28, carried by the frame member 1, rides when the gate is moving to closed position, the track positively guiding the shank into engagement with the locking latch 29 and supporting the weight of the end of the gate while in closed position.

To prevent the gate from being lifted after it has been closed, a block 30 is formed on the face of the plate 25 and extends laterally above the track 27, the space between the plate and block being sufficient to receive the shank 28, consequently the gate can not be raised or lowered so long as the shank is positioned between the track and block, the ends of the track and block being curved so that the shank will readily ride into the passage between the track and block.

The track 27 is greater in width than the block 30 to provide space for the latch 29, the combined width of the block and latch being substantially the same as the width of the track so that the lower edge of the latch normally rests upon the track, and as the ends of the latch are rounded or curved, it will readily ride over the shank as the gate swings to closed position. The lower edge face of the latch 29 is provided with a notch

31, the end walls 32 of which are inclined inwardly and underhang the shank 28 when the shank moves into engagement with either end wall, this action preventing the latch 5 bouncing upwardly from the impact sufficiently to release the shank, thus forming a positive lock.

The latch 29 is held in position above the track 27 by studs 33, which project from the 10 block 30 and extend through inverted L-shaped slots 34 in the latch, said slots being opposed to each other and so located that when one of the studs is seated at the closed end of one of the horizontal portions of one 15 slot, the other stud will be in position to enter the vertical portion of the other slot, consequently that end of the latch containing the slot with which the stud is in registration with the vertical portion of the slot, may be 20 elevated or moved away from the track to admit the shank, while the opposite end of the latch pivots on the other stud and is held against upward movement, thus forming a positive stop for the shank. As soon as the 25 shank passes into registration with the notch 31, the elevated end of the latch will instantly descend by gravity, thus placing an inclined wall of the notch in the path of the shank in both directions and preventing 30 the escape of the shank from the notch until the latch is manually operated to raise one end of the latch and thus move one of the end walls of the notch out of the path of the shank.

35 As shown in Fig. 7, the latch 29 is positioned for the gate to open or close from the right hand side, the position of the latch, when closed, being shown in full lines and in its open position by dotted lines, but if the 40 gate is to be opened in the opposite direction, the latch is moved longitudinally until the vertical portion of the slot 34 at the left hand end of the latch is in registration with the stud in said slot, thus reversing the action 45 of the latch. The latch 29 is held in position on the studs 33 in any suitable manner, preferably by upsetting the free ends of the studs to form heads 35.

Supposing the gate to be in closed position, to release the same from the latch structure so that the gate may be opened, the handle portion 36 of the latch 29 is grasped and the latch moved bodily in the direction in which the gate is to be swung and the latch 55 then manually elevated at one end for moving the end wall of the notch 31 out of the path of the shank 28, when the gate may be swung to open position. The latch is then released, when the end thereof, elevated to 60 release the shank, will descend by gravity and be in position to automatically elevate when the shank again rides over the track 27 during the closing movement of the gate.

By entering the ends of the bars 5 between 65 the pins 6 and 7 and the bolts 8 and 9 as

shown, the outer end of the gate may be elevated to pass over an obstruction, such as snow or the like, or elevated, as shown in Fig. 5 of the drawings to provide a space below the gate for the passage of small animals, and when so used, the end of the gate 70 may be permanently held in elevated position by engaging the lower tensioning hook 17 with the latch mechanism.

The invention claimed is:

1. A gate structure including a plurality of bars disposed horizontally, a U-shaped frame member at the front and rear ends of said bars, a pair of angular shaped supporting members adjacent the rear ends of said bars, 80 means for holding the supporting members in spaced relation with the rear frame member, bolts extending transversely through said supporting members below the bars passing therebetween, and similar bolts passing 85 transversely through the rear frame member and above the ends of said bars, whereby the bars will fulcrum on the bolts through the supporting members when the forward ends of the bars are elevated and 90 the rear ends of the bars move independently of the rear frame member.

2. A gate structure including a front and rear frame member, bars having their ends removably engaged with said frame members, a pair of brace members cooperating with said bars between their ends, a pair of supporting members, means for attaching the supporting members to the rear frame member and space the same therefrom, tensioning wires at the upper and lower edges of the gate for holding the frame members and bars in assembled relation and the brace members in spaced position, means for holding the bars in spaced relation, and means 100 for raising and lowering the supporting members for determining the elevation of said bars comprising a clevis having its lower ends connected to said supporting members, a bolt having a hook terminal for 105 engagement with said clevis, and means for adjustably attaching said bolt to the rear frame member.

3. A gate structure including a plurality of bars, a frame member at each end of said bars for loosely receiving the ends of said bars, supporting members for the bars, means for connecting said supporting members with one of the frame members, brace members for the bars positioned between the 115 frame members, wires connecting the ends of the brace members with the ends of the supporting members, wires extending from the brace members to the forward frame member, and tension hooks adjustably connected 120 with the front frame member to which the latter wires are attached for holding the frame members in engagement with the ends of the bars and holding the brace members in spaced position.

4. In a gate structure, a plurality of horizontally disposed bars, frame members fitting over the ends of said bars, supporting members adjacent the rear frame member, a clevis attached at one end to the supporting members, a bolt having a hook terminal for engagement with the clevis, said bolt passing through parts of the rear frame member, means for adjusting said bolt longi-

tudinally, and means carried by said supporting members and the rear frame member for elevating the forward portion of said bars when the supporting members are elevated.

5. In testimony whereof I hereto affix my signature.

HARRY A. BURGESS.
